UNITED STATES PATENT OFFICE.

ANTHONY O'MALLEY, OF FLUSHING, NEW YORK.

MUSICAL INSTRUMENT.

Application filed December 18, 1924. Serial No. 756,652.

This invention relates to musical instruments of the type known as "wind instruments" as flutes, piccolos, clarinets, and all other instruments having the distinguishing 5 characteristic of tone holes in the body of the instrument communicating with the interior thereof.

In the manufacture of those types of musical instruments, great care must be taken in 10 locating the tone holes to produce the exact pitch desired, which could not be attained in case the tone holes are even slightly misplaced.

In many cases, the displacement of the 15 tone holes, while tuning the wind instrument to the pitch of a piano or any other instrument is found a necessity. It is practically impossible to accurately set these tone holes in the present type of wind instruments. 20 Very frequently it is attempted to adjust these instruments by shifting the tuning slide, a feat which is very difficult to accomplish, for a slight displacement of even a small fraction of an inch will put the instrument out of tune.

To overcome these difficulties, I propose certain adjusting means to enable the accurate setting of all or any of the individual tone holes, as well as the mouthpiece.

30 In the accompanying drawings, I have illustrated an embodiment of my invention as fully described in this specification.

Fig. 1 represents a plan view, partly broken, of the key part of a wind instrument.

35 Fig. 2 represents an enlarged sectional view along lines 2—2 of Fig. 1.

Fig. 3 represents an enlarged side view along lines 3—3 of Fig. 1.

40 Fig. 4 represents a sectional view along lines 4—4 of Fig. 3.

Fig. 5 represents a sectional view along lines 5—5 of Fig. 3.

Fig. 6 represents a sectional view of a modified form of sliding arrangements.

45 Fig. 7 represents a top view of the tubular body 1^a, shown in Fig. 6.

Fig. 8 represents a sectional view along lines 8—8 of Fig. 7.

Fig. 9 represents a top view of the sliding shield 26, shown in Fig. 6.

50 Fig. 10 represents a sectional view along lines 10—10 of Fig. 9.

Fig. 11 represents the individual sliding shield "28" carrying the tone hole proper.

55 Fig. 12 represents a sectional view along lines 12—12 of Fig. 11.

Fig. 13 represents the adjustable mouth piece.

Fig. 14 represents a sectional view along lines 14—14 of Fig. 13.

The same reference characters indicate the same parts in all the figures.

For the purpose of clearly indicating the features of my invention, the simplest elemental form of the key portion of a "wind instrument" is shown illustrated in the drawings, it being obvious that the same features are applicable to any known type or construction of wind instrument. In the drawings, 1, represents the body or main tube, 70 upon which another sliding tube or sleeve 2, is adjustably arranged.

A number of oblong perforations 3, one for each tone hole, are provided in body 1. A corresponding number of oblong perforations 4, of the same width but only half of the length of perforations 3, are provided in, and located directly above perforations 3, in sliding tube 2. Perforations 4, can be set and adjusted in any desired position over 75 perforations 3, by means of the set screw arrangement 5, (see Figs. 3 and 5), which consists of a narrow slot 6, provided in body 1, a specially shaped sliding nut 7, a portion of which is entering and sliding in slot 6. A 80 hole 8, suitably located in sliding tube 2, permits set screws 5, to engage with the nut 7, and securely adjust perforations 4, in any position over perforations 3.

An indicating arrangement, shown in Fig. 90 3, consisting of a graduated scale 9, engraved on body 1, and a suitable observation slot 10, provided with a pointer 11, in sliding tube 2, serves the purpose of accurate adjustment 95 and resetting of the instrument.

The tone hole adjustment, as shown in Figs. 1, 2, 3 and 4, consists of the sliding body 12, closely fitting over tube 2, the tone hole 13, surrounded by collar 14, so located as to correspond with the oblong holes in 100 body 1, and sliding tube 2.

A stopper 15, closing tone hole 13, forming one part with finger key 16, is pivoted between bearings 17 and 17', these bearings are rigidly connected to sliding body 12. 105 A spring 25, tends to hold stopper 15, normally in the closed position as shown in Fig. 4.

Provision is made for the final and most accurate adjustment of the location of tone 110 holes by specially provided clamping means on bearings 17 and 17' which bearings are

provided with a slot 18 as shown in Fig. 4. A clamp screw 19, serves the purpose of loosening the grip upon the guide rod 20, when adjustment is desired or tightening the grip upon rod 20, when final adjustment is accomplished. Guide rod 20, is rigidly held in place by bearings 21, which in turn are permanently mounted upon sliding tube 2. Another indicating arrangement especially provided for sliding body 12, as shown in Fig. 3, consisting of a graduated scale 22, engraved upon sliding tube 2, and a suitable observation slot 23 provided with a pointer 24, permits accurate adjustment, or if desired 15 a resetting of the position of the tone hole.

In case it is desired to change the pitch of all tone holes, then only one adjustment is required; this is accomplished by loosening set screw 5, and shifting sliding tube 2, in either direction, depending on the pitch of tune, desired, after the proper location is determined set screw 5 is to be firmly tightened again. If a more accurate adjustment of the individual tone holes is found necessary, then screws 19 of bearings 17 are loosened and the tone hole sliding body 12, is shifted in either direction, depending on the final pitch of tune desired, after which set screws 19 are firmly tightened again.

30 The graduation of the indicating scales may be properly marked and these markings compiled in form of a table so as to enable the player to set his instrument for any tune pitch desired without further experimenting.

For reasons of simplicity in the manufacture of my improved type of wind instruments, all the adjustable sliding parts are made tubular which obviously permits great 40 accuracy in fitting and calibrating of the sliding parts. In Figs. 6 to 12, a modified construction of the sliding parts is illustrated, in case the tubular design of same is not desirable. Upon the body or main tube 1^A (Fig. 6) a semi-circular sliding cover 26, is movably mounted and held in place by slide channels 27 and 27'. Sliding cover 26, takes the place of sliding tube 2, shown in Figs. 1, 2, 3 and 4.

50 Another shorter sliding shield 28, is movably mounted and held in place by slide channel 29, and guide rod 20^A. This shield 28 takes the place of sliding tube 12, shown in Figs. 1, 2, 3 and 4.

55 Another feature of the modified construction is the replacement of the oblong slots 3, as shown in Figs. 1 and 2, by one continuous slot 3^A, of proper length. The functioning and adjusting of this modified construction is otherwise the same as described for Figs 1 to 5 and all similar features are indicated by the same numerals.

The mouthpiece 30, as shown in Figs. 13 and 14 is also adjustably arranged. This 60 mouthpiece, mounted upon the end part 31,

of a wind instrument is provided with a specially arranged blow hole 32, whose neckpiece 33, extends into a slot 34, in end part 31. The inner end of neckpiece 33 is provided with a flange 33^A, so dimensioned as to permit the mouthpiece to slide forth and back within the limits of slot 34. A set screw 35, nuts 36, and suitable slot 37, for nut 36, all similarly arranged as described in Figs. 3 and 5, complete the adjusting arrangement for mouthpiece 30.

Having thus duly described and illustrated embodiments of my invention, I do not wish to be limited to the exact construction of the instruments shown, inasmuch as for reasons of simplicity, the most primitive and simplest form of embodiments have been shown, and it being apparent that there may be considerable variation in the design of the instrument as well as in utilizing the principles disclosed without departing from the spirit of my invention.

What I claim and desire to secure by Letters Patent is:—

1. In a musical instrument of the wind type, the combination of an adjustable mouthpiece, a plurality of adjustable tone holes, suitable indicating means for a predetermined setting of said mouthpiece and tone holes to any desired pitch of tune.

2. In a musical instrument of the wind type, the combination of a tubular body, said tubular body provided with a plurality of suitably located oblong holes, a tubular cover slidably arranged over said tubular body, oblong holes of the number and spacing as those of the tubular body, and so located as to correspond with the holes of the tubular body, suitable adjusting means to properly adjust and set the relative position of the tubular cover and its holes, and suitable indicating means for said adjustment.

3. In a musical instrument of the wind type, the combination of a tubular body, a plurality of oblong holes suitably located upon said tubular body, a suitable tubular cover slidably arranged upon said tubular body, a plurality of suitable oblong holes suitably arranged and located upon said tubular cover, a plurality of suitable tone hole pieces slidably arranged upon said tubular cover, and suitable adjusting means for collectively adjusting the relative positions of the tubular body, the sliding cover piece, and the tone hole pieces and their respective tone holes to each other.

4. In a musical instrument of the wind type, the combination of a tubular body, a plurality of suitable oblong tone holes suitably located upon said tubular body, a suitable tubular cover slidably arranged upon said tubular body, a plurality of suitable oblong holes suitably arranged and located upon said tubular cover, a plurality of suitable

ble tone hole pieces, said tone hole pieces individually slidably arranged upon said tubular cover, suitable adjusting means for individually adjusting the relative positions of the tubular body, the sliding cover, and the individual tone hole pieces and their respective tone holes to each other, and a plurality of individual indicating means for said individual adjustments.

10. 5. In a musical instrument of the character described, a tubular sliding cover, suitable adjusting means for said tubular sliding cover, and indicating means comprising a perforated window provided with a suitable indicator, and a suitably arranged indicating scale.

6. In a musical instrument of the character described, a sliding tone hole piece comprising a suitable tubular body, a suitable tone hole provided on said tubular body, a suitable stopper for opening and closing said tone hole, suitable operating means for actuating said stopper, suitable adjusting means to locate and set said sliding tone hole piece, and suitable indicating means to fa-

cilitate the adjustment and setting of the tone hole piece.

7. In a musical instrument of the character described, a sliding tone hole piece comprising a suitable body, a suitable tone hole provided on said body, a suitable stopper for opening and closing said tone hole, suitable operating means for actuating said stopper, suitable adjusting means to locate and set said sliding tone hole piece and suitable indicating means to facilitate the adjustment and setting of the tone hole piece.

8. In a musical instrument of the character described, an adjustable mouthpiece, said mouthpiece slidably arranged upon the body of the instrument, suitable clamping means to permanently secure the setting of said mouthpiece, and suitable indicating means for a predetermined adjustment of said mouthpiece.

Signed at city of New York in the county of N. Y. and State of New York.

ANTHONY O'MALLEY.
